UNITED STATES PATENT OFFICE.

CARLISLE F. BAPTIST, SR., OF RICHMOND, VIRGINIA.

JEWEL-SETTING TOOL.

1,370,873.

Specification of Letters Patent.

Patented Mar. 8, 1921.

Application filed May 3, 1920. Serial No. 279,901.

To all whom it may concern:

Be it known that I, CARLISLE F. BAPTIST, Sr., a citizen of the United States, residing at and whose post-office address is 14 North 5 30th street, city of Richmond, county of Henrico, State of Virginia, have invented certain new and useful Improvements in Jewel-Setting Tools; and I do hereby declare the following to be a full, clear, and 10 exact description of the invention, such as will enable others skilled in the art to which it appertains to make and use the same.

The invention relates to a simple and efficient tool for setting the jewels in double 15 roller-tables of watches and the like, as will be more particularly described in the annexed specification and illustrated in connection with the accompanying drawings in which latter:—

20 Figure 1 is a plan view of the preferred form of the tool.

Fig. 2 is a bottom plan thereof.

Fig. 3 is a vertical transverse section through the device, on a considerably enlarged scale.

25 Fig. 4 is a perspective view of the roller-table supporting and jewel clamping bushing.

Referring to the drawings, 1 indicates a 30 base or support which may be conveniently made in disk form, the back portion of which is turned out to leave an annular central projection 3, and a peripheral flange 2. The upper face of the base, which is otherwise flat, is provided with a transverse recess 4, provided with a central circular depression 5, preferably located at the center 35 of the base. Secured to one side of the base, and preferably at right angles to the trans- 40 verse recess 4, is a handle 6 by means of which the tool is supported.

Pivoted on a suitable screw stud 11, near one end of the recess 4, is a lever 10, having a cut-away central portion terminating in a 45 knife edge 12 which normally engages the adjacent wall of the recess, against which the lever is held by means of a spring 13, secured by a screw 14 to the face of the base. One of the lateral walls of the recess 4 is 50 tapered or divergent with respect to the other side to permit a limited movement of the lever 10 in the recess and permit the lever to be swung so that its upper edge moves out of engagement with the opposite 55 wall of the recess.

Piercing the base 1, and excising a small

section of the upper wall of the recess 4, is a circular opening 19 in which is situated a bushing 15, preferably of steel or other hard metal, which is adapted to be locked in adjusted position within the opening 19, by a set-screw 20 passing through the flange 2 of the base and into the peripheral edge of the central projection 3, as shown in Figs. 2 and 3. Said bushing is provided with an eccentric bore 16, which intercepts or excises the side wall of the bushing and forms two horn-like clamping members 18 which are separated by a short interval and serve as two of the clamping elements for the jewel 70 to be set. The lateral wall of the bushing 15 is provided with a cross-cut 17 below the clamping jaws 18, as shown in Fig. 4 to provide an open space to admit one edge of the jewel-supporting table.

75 Mounted for vertical adjustment in the central recess 5 in the base, and lying below the bottom of the groove 4 is a jewel supporting table 23 which is provided with a central screw-threaded stem 24 which engages a screw-threaded opening in the center of the depression 5 in the base, so that, by turning the threaded stem 24, the table 23 is raised or lowered to accommodate jewels of different lengths and to effect the 85 nicety of adjustment required, the threads in the stem 24 are preferably made very fine. The table 23 is preferably made of very thin steel so that the thickness of the peripheral edge of the table may be reduced to clear the 90 lower flange of a double roller-table when the latter is applied to its proper position within the bore 16 of the bushing 15, as illustrated in Fig. 3.

95 In applying the tool to its intended use, the jewel to be set in the double roller-table is clamped in position between the clamping jaws 18 and the bushing 15 and the knife edge 12 of the lever 10, with the lower end of the jewel resting on the supporting table 23, as shown at X in Fig. 3, said table 23 having been properly adjusted to the length of the jewel. The double roller-table is then dropped into the eccentric bore 16 of the bushing 15 and canted slightly to cause 105 the lower flange of the roller-table to clear the marginal edge of the jewel supporting table 23, the roller-table being then adjusted to bring the jewel socket in the upper flange into registry with the upper end of the jewel 110 and, inasmuch as the jewel is rigidly held in position by the clamping jaws 18, the knife

edge of the lever and the table 23, it will be obvious that the jewel may be quickly and accurately applied in its socket on the lower face of the upper flange of the roller-table without danger of displacing any of the parts. After the jewel has been thus inserted in position in the roller-table, the lever 10 is retracted thereby freeing the jewel and permitting the roller-table with the engaged jewel to be removed, the removal being effected by canting the roller-table slightly and lifting it out of the bore of the bushing 15.

The bushing 15, it will be noted, is removable and may be replaced by similar bushings having different sized bores to accommodate various size roller-tables. Also, as heretofore indicated, the jewel supporting table 23 is adjustable to permit the device to be used in setting jewels of different lengths and also to coöperate with the various sized bushings employed. While these features of the variable bore bushings and adjustable jewel supporting table are highly desirable in a tool of this character, to permit the same to operate with various sized double roller-tables and variable length jewels, it is nevertheless to be understood that the invention is not limited to either the removable and replaceable bushings or to the adjustable table, as it is obvious that the tool may be constructed with a single fixed bushing and also a fixed table which will enable the tool to be used for setting jewels in a single type of double roller bearing without requiring any adjustment or substitution of a different sized bushing or any vertical adjustment of the table. Likewise, the shape or configuration of the tool as a whole may be varied to accommodate the exigencies of any class of work, or the convenience of the operator, provided, however, that the essential characteristics of the device, involving the particular relation of the eccentrically bored bushing with its spaced clamping jaws, the pivoted lever with its knife edge, and the means of supporting the lower end of the jewel when the latter is clamped between the jaws and the knife edge, are preserved.

50 What I claim as my invention is:

1. A jewel setting tool comprising a base, a transverse recess in the top thereof, a roller-table supporting bushing mounted in the base having an eccentric bore terminating in jewel clamping jaws substantially coincident with one wall of said transverse recess, and a lever pivoted to the base for

transverse movement in said recess to coöperate with the jaws of the bushing to hold the jewel in position.

60 2. A jewel setting tool comprising a base, a jewel supporting table mounted in said base, a roller-table supporting bushing mounted in said base adjacent the table and having an eccentric bore terminating in jewel clamping jaws, and a lever pivoted to said base having a knife edge coöperating with the jaws of the bushing to hold the jewel.

65 3. A jewel setting tool comprising a base having a recess in its top, a jewel supporting table adjustably mounted in said recess, a roller-table supporting bushing mounted in an opening in said base adjacent one wall of said recess said bushing having an eccentric bore terminating in lateral jewel clamping jaws, and a lever pivoted to the base having a knife edge coöperating with the jaws of the bushing to hold the jewel.

70 4. A jewel setting tool comprising a base having a transverse recess and a circular recess in its top face, the circular recess opening into the transverse recess at one point, a roller-table supporting bushing mounted in said circular recess and having an eccentric bore terminating in jewel clamping jaws at 75 one side of the bushing lying in the opening between said recesses, and a lever pivoted at one end in said transverse recess and coöperating with the jaws of the bushing to hold the jewel.

75 5. A jewel setting tool comprising a base having a transverse recess and a depression in said recess, a jewel supporting table adjustably mounted in said depression, a recess in the base opening into the transverse 80 recess, a roller-table supporting bushing mounted in said last named recess, said bushing having an eccentric bore terminating in jewel-clamping jaws at one side of the bushing lying in the opening between said 85 recesses, and a lever pivoted at one end in said transverse recess and coöperating with the jaws of the bushing to hold the jewel.

90 6. A jewel setting tool comprising a base, a lever pivoted at one end to the base, and an eccentrically bored bushing mounted in an opening in the base and having lateral jaws formed by the bore excising the side walls of the bushing, the jaws of the bushing coöperating with the lever to clamp a 95 jewel to be set in a roller-table mounted in the bore of the bushing.

100 In testimony whereof I affix my signature.
CARLISLE F. BAPTIST, Sr.
